(57) **CLAIM**

We claim the ornamental design for an holder for use with a vertical pole, as shown and described.

DESCRIPTION

FIG. 1 is a perspective view of the holder for use with a vertical pole of our new design according to a first embodiment, shown in its ordinary environment holding a glass;

FIG. 2 is a perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom plan view thereof;

FIG. 9 is a perspective view of the holder for use with a vertical pole of our new design according to a second embodiment, shown in its ordinary environment holding a glass;

FIG. 10 is a perspective view thereof;

FIG. 11 is a front elevation view thereof;

FIG. 12 is a rear elevation view thereof;

FIG. 13 is a right side view thereof;

FIG. 14 is a left side view thereof;

FIG. 15 is a top plan view thereof; and,

FIG. 16 is a bottom plan view thereof.

The broken lines are for the purpose of illustrating environmental structure and form no part of the claimed design.
